FRANKLIN A. REECE, OF BROOKLINE, MASSACHUSETTS, ASSIGNOR TO THE REECE
BUTTON HOLE MACHINE COMPANY, OF BOSTON, MASSACHUSETTS, A CORPORATION
OF MAINE

LOOPER-ADJUSTING MEANS FOR BUTTONHOLE SEWING MACHINES

Application filed October 6, 1931. Serial No. 567,183.

This invention relates to buttonhole sewing machines of that type in which the stitch-forming mechanism comprises a needle operating from above the work and looper mechanism operating beneath the work and co-operating with the needle to produce the stitches.

The principal object of the present invention is to provide improved means for adjusting the timing of the looper mechanism relating to the needle without, however, changing the position of the loopers relative to the needle while the adjustment is being made.

In order that buttonhole stitches may be properly formed it is essential that the movement of the loopers be correctly timed to coordinate with that of the needle and in making buttonhole stitches of different types or in goods of different character it is sometimes desirable to adjust or change the timing to suit the different conditions or requirements.

For instance, when the stitch-forming mechanism of a buttonhole sewing machine employing two loopers is adjusted to make a change in the bight of the buttonhole stitch, (the term "bight" being used to indicate the length of the stitch transversely of the buttonhole slit) it is necessary to change slightly the timing of the looper movements with reference to the needle movements in order that at each stitch the loopers may engage properly the loop thrown out by the needle.

The present invention provides a simple means for thus adjusting or varying the timing of the loopers while the sewing machine is at rest but without changing the relative position of the needle and looper while the change in timing is being effected.

In order to give an understanding of the invention I have illustrated in the drawings a selected embodiment thereof which will now be described after which the novel features will be pointed out in the appended claims.

In the drawings:

Fig. 1 is a side view of a sewing machine embodying my invention with parts broken out;

Fig. 2 is a fragmentary view illustrating the means for changing the timing of the looper relative to the movement of the needle;

Fig. 3 is a section on the line 3—3, Fig. 2; Fig. 4 is a view of the turret with the looper and looper-operating mechanism thereon;

As stated above the sewing machine herein illustrated is of the type comprising a reciprocating needle operating from above the work and looper mechanism mounted on a turret beneath the work and co-operating with the needle to concatenate the stitches.

The needle is shown at 1 and it is carried by the usual needle bar 2 which is mounted for vertical reciprocation in the head 3 of the stitch frame 4, said needle bar receiving its reciprocation through the lever 5 situated within the frame 4 and pivoted to turn about the axis 6, said lever 5 having a follower 7 operating in a groove 8 in a cam element 9 which is mounted on a cam shaft 10. The rotation of the cam thus vibrates the lever and reciprocates the needle bar 2.

The sewing machine herein shown is of the type in which the needle has a needle-jogging movement, such jogging movement being produced by the mechanism usually employed for this purpose and which comprises a vertically-reciprocating sleeve 34 through which the needle bar operates and which is given a lateral vibration as it reciprocates. This sleeve is reciprocated through a rocker device 35 having an arm 36 which is connected by a link 37 to a cam-actuated lever 38 pivoted to the frame at 39. The amplitude of jogging movement is adjusted by shifting the pivotal connection of the link 37 with the arm 36 longitudinally of the slot 40 with which said arm is provided.

The looper mechanism comprises the two loopers 11 and their looper spreaders 12 which are mounted on an oscillating block 13 pivoted at 14 on a turret 15 which is situated beneath the work and is carried by the portion 16 of the frame 4. It will be understood, of course, that both the turret and the needle bar rotate about a vertical axis in sewing around the end of the buttonhole, this being a common practice in buttonhole sewing machines.

The looper carrying block 13 derives its oscillation from a cam groove 17 formed in the cam element 9.

The connection between the cam groove 17 and the looper block is similar in many respects to that usually employed in sewing machines of this type. Such connection comprises a lever 18 pivoted at 19 and provided with a follower 20 operating in the cam groove 17, said lever being connected by a link 21 to another lever 22 which is pivoted at 23 to the portion 16 of the frame 4. The lever 22 is pivotally connected at 24 to the lower end of a spindle 25 which is situated axially of the turret 15 and is mounted for vertical reciprocation therein and said spindle 25 is connected to the looper-carrying block 13 by means of a link 26. The vibrating movement of the lever 18 is thus transmitted to the looper-carrying block 13 thereby to give the loopers their necessary vibrating movement.

20 The cam grooves 17 and 8 from which the looper mechanism and the needle derive their movement are formed in the same cam element and thus have a constant non-adjustable relation to each other.

25 In the operation of a buttonhole sewing machine having two loopers it is sometimes necessary to make an adjustment in the timing of the looper movements relative to the needle movements and as an example of the 30 necessity of making such adjustment I would refer to the fact that when the stitch-forming mechanism is adjusted to change the bight of the buttonhole stitch it is also necessary to make a corresponding adjustment in the timing of the movement of the two loopers relative to the needle movements in order that the loopers may properly perform their function. In the present invention the adjustment of the timing between the loopers 40 and the needle is secured by adjusting the relative positions of the followers 20 and 7 in the cam grooves 17 and 8 and the present invention provides for making such adjustment while the machine is at rest and without changing the relative position of the looper and needle at the time of the adjustment.

45 The lever 18 is pivoted at 19 to a disk 27 that is carried in a portion 28 of the frame. 50 The pivotal point 19 is situated eccentrically of the disk 27 as best seen in Fig. 2 so that a rotative or turning movement of the disk 27 in the portion 28 of the frame will shift the pivot point of the lever and thereby shift the 55 position of the follower 20 in the groove 17.

The parts are so designed that when the machine comes to rest the cam groove 17 will be in the position shown in Fig. 2 and the follower 20 will be at the bottom of this 60 groove and located substantially in the vertical line of the axis of the cam, and the pivotal point 19 will be on its low center.

65 With the parts in the position shown in Fig. 2 it will be observed that if the disk 27 is turned slightly in either direction the pivot

point 19 will be moved either to the right or to the left thereby shifting the position of the follower 20 to the right or the left in the groove 17. Any such movement of the follower 20 to the right or the left from the position shown in Fig. 1 will cause the follower to rise slightly because in Fig. 1 it is at the low point of the cam groove.

70 The construction herein shown is such that the shifting of the follower 20 in the cam groove 17 in either direction from the position shown in Fig. 1 may be effected without causing any vertical movement in the link 21 and consequently without producing any movement in the looper. Owing to the fact 75 that the pivotal connection 19 of the lever 18 and the disk 27 is at its low center it follows that whenever the disk 27 is turned in either direction to effect an adjustment of the follower 20 in the cam groove 17 the end 80 of the lever which is pivoted to the disk 27 will also have a rising movement as it follows an arcuate path struck from the center of the disk 27. The radius of this arcuate path, 85 however, is less than the radius of the cam groove 17 so that as the disk 27 is turned slightly to make an adjustment the pivoted end 19 will rise faster than the follower 20 and will thereby tend to shift the angular 90 position of the lever 18 sufficiently to maintain the stationary position of the link 21 notwithstanding the fact that the follower 20 has been lifted slightly by the upward curvature of the cam track 17.

95 The device, therefore, provides for shifting the position of the follower 20 in the cam path 17 when the latter is stationary without, 100 however, producing any rising movement of the link 21 and consequent change of position of the loopers. In other words, the shifting of the follower 20 in the cam groove 17 changes the timing of the looper movements 105 relative to the needle movements without producing any positional displacement of the looper or the needles.

110 In practice it is sufficient to be able to vary this timing within relatively narrow limits and the degree of shifting of the position of the pivot 19 which the disk 27 provides for gives all the adjustment which will be necessary.

115 Means are provided for locking the disk 27 in any adjusted position, such means being in the form of a locking block 29 operating in a recess 30 in the portion 28 of the frame and 120 having a rib 31 adapted to engage in a groove 32 formed peripherally of the disk 27. This locking or friction block 29 is formed into locking engagement with the disk by a set screw 33 which is screw threaded into the 125 end of the recess 30.

I claim.

130 1. In a sewing machine, the combination with looper mechanism, means to actuate the latter comprising a pivoted lever, a cam for

actuating said lever and means for adjusting the pivotal point of the lever relative to said cam.

2. In a sewing machine, the combination with looper mechanism, means for actuating the latter comprising a rotary cam, a lever actuated by said cam, and an adjustable member to which the lever is pivoted, adjustment of said member shifting the position of the lever relative to the cam.

3. In a sewing machine, the combination with looper mechanism, means for actuating the latter comprising a rotary cam, a lever actuated by said cam, and a disk mounted for turning movement about its center and to which the lever is eccentrically pivoted.

4. In a sewing machine, the combination with a needle operating from above the work, of needle-operating mechanism, looper mechanism co-operating with the needle to concatenate the stitches, looper actuating mechanism including a cam and a pivoted lever actuated by said cam and an adjustable member to which said lever is pivoted, adjustment of said member shifting the position of the lever relative to said cam, thereby varying the timing of the looper relative to the needle movements.

5. In testimony whereof, I have signed my name to this specification.

FRANKLIN A. REECE.
